CAM GRINDING MACHINE

Harry W. Brown, Cleveland, Ohio, assignor to
 The National Acme Company, Cleveland, Ohio,
 a corporation of Ohio

Application December 18, 1943, Serial No. 514,806

13 Claims. (Cl. 51—101)

1

This invention relates to machines for grinding internal and external cams and more particularly to what are known as accelerating cam grinding machines, the principal object being the provision of a machine capable of grinding multiple cam surfaces on either the inner or outer peripheral surface of a work piece such as a die cup for dies.

A further object of the present invention is the provision of a cam grinding machine provided with a reciprocal table having a very slight movement of as little as $\frac{1}{64}$ " with a very rapid back and forth motion.

A further object of the invention is the provision of means for rotating the work holding table to permit the grinding of tapered cam surfaces.

A still further object of the invention is the provision of a reciprocating table adapted to move the grinding tool at right angles to the reciprocating movement of the work holding table.

A still further object of the invention is the provision of means for rotating the spindle of the work holding head in which provision is made for changing the ratio of rotation of the work holding means relative to the master cam in order to grind a variable number of cam surfaces.

A still further object of the invention is the provision of hydraulic or fluid means for operating many of the parts of the machine in proper timed relation.

A still further object of the invention is the provision of such a machine that will be simple in construction, efficient and highly accurate in use and, at the same time, comparatively inexpensive to manufacture.

In the drawings accompanying and forming a part of this specification,

Fig. 1 is a side elevation of this improved machine.

Fig. 2 is a view of one end of the machine taken at right angles to Fig. 1.

Fig. 3 is a view taken on line 3—3 of Fig. 7.

Fig. 4 is a view of the opposite end of the machine to that shown in Fig. 2 and illustrates the gearing for rotating the work at variable speeds.

Fig. 5 is a detail of the operating handle and its shock absorbing means.

Fig. 6 is a detail of the operating handle taken at right angles to Fig. 5.

Fig. 7 is a longitudinal section through the work carrying head somewhat enlarged and showing the spindle connection with the driving means and the manner in which the head may be rotated for grinding angular surfaces.

2

Fig. 8 is an enlarged detail view showing the master cam and its associated parts for operating the transverse slide.

Fig. 9 is a section taken on line 9—9 of Fig. 8.

Fig. 10 is a section taken on line 10—10 of Fig. 8, and

Fig. 11 is a detail or layout of the hydraulic or fluid operating system.

Similar characters of reference indicate corresponding parts in the several views.

Before explaining in detail the present invention and mode of operation thereof, I desire to have it understood that the invention is not limited to the details of construction and arrangement of parts illustrated in the accompanying drawings since the invention is capable of other embodiments, and that the phraseology employed is for the purpose of description and not of limitation.

20 The present machine comprises in general a base or frame 2 of any suitable size and shape housing the various parts of the hydraulic or fluid operating mechanism. Upon this base is mounted a shiftable or reciprocal table 3 having secured thereto in any suitable manner a work holding head 4 and supported on the frame 2 at one end thereof is a rotatable tool holding member 5 suitably carried for reciprocal movement transversely of the table 3.

30 For a better understanding of the machine, the operation and structure of the various parts will be described separately.

The driving and controlling means for the table 3 in the present instance is hydraulically controlled by means of a double-acting hydraulic pump A. This pump receives fluid from a reservoir 6 by means of the suction line Y and is suitably driven from a motor 7 connected to the pump by a belt 8 and pulley wheel 9.

40 This double pump is provided with a high pressure low volume line R leading from the high pressure side of the pump running through a flow control valve P to a four-way pilot valve B and then to either end of a cylinder 10 attached to the under side of the table 3. The course of the fluid at each end of the cylinder is indicated by arrows and it will thus be seen that the passage to either end of the cylinder 10 will cause the cylinder housing 11 to be shifted either to the

45 right or left and with it the table 3 and work holding head 4 will be reciprocated at any desired stroke or speed controlled by the flow control valve P.

50 A spring pressed lever 12 is provided at the front of the base of the machine and when this

lever is pressed in, (see Fig. 6) the machine is started and when it is pulled out the machine is stopped.

When in its engaged position (inward) the lever 12 is adapted to be engaged by adjustable dogs or lugs 13 suitably fastened to the side of the slide 3 and contact with these dogs 13 will cause the lever 12 to be rocked sideways to the left and right. The opposite end of the lever 12 is connected by means of linkage 14 to a pilot valve E which is connected through the line S to the low pressure high volume side of the pump A and to the four-way pilot valve B to control the direction of movement of the table 3 and head 4.

On certain classes of work, the stroke or reciprocating movement of the table has to be very short and this machine permits this stroke to be as short as $\frac{1}{8}$ " and shock to the valve which would ordinarily result from such a short stroke when reciprocating at high speed is prevented by means of the spring E'.

The work holding head 4 carried by this reciprocating table 3 is provided with a rotatable spindle 15 having at one end thereof a chuck or work holding member 16 for the reception of the work piece indicated in the present instance as 17.

A fluid motor F controlled by a four-way manually operated valve D and a flow control valve N is provided for driving and controlling the desired speed of the rotating spindle 15.

This motor F is connected through a chain of gears 18 with a splined shaft 19 which, in turn, is connected through beveled gearing 20 to a beveled gear 21 on the spindle shaft 15 of the head 4. To eliminate any backlash of the gears, in view of the train of gears required, a spring tension brake 22 (see Figs. 1, 3 and 7) is provided on the end of the spindle and this brake prevents any backlash or lost motion.

In the particular structure illustrated, the machine is designed to grind four cam surfaces on the inner periphery of a work piece and the gearing 18, 19, 20 and 21 is so constructed and proportioned that the spindle 15 will be rotated at the proper speed for the grinding of four cam surfaces. However, should it be desired to grind a greater or lesser number of cam surfaces, provision has been made to vary the speed of rotation of the spindle 15 as may be deemed necessary.

Intermediate the gear train 18, a swinging arm 23 is provided and by merely changing the position of this arm and substituting the proper gear, the speed of the spindle 15 may be changed. The ratio of speed of this spindle to the speed of the master cam hereinafter to be described must at all times be relative.

Since the cams have to be ground in various shapes, length of grooves, taper or straight, an adjustable work holding head has been provided so that this head may be set at any desired horizontal angle relative to the grinding tool. For that reason, the bevel gear box 24 and bevel gear drive 20, 21 is built in such manner that the work holding head 4 may be rotated at any angle relative to the tool for different classes of work without affecting the drive of the work spindle 15. It will be noted that the swinging or rotating of the housing 4 on the table 3 will cause the gear 21 to rotate around its meshing bevel gear of the train 20.

Located at one end of the machine is the grinder unit 5 having a rotatable spindle 25 carrying a suitable grinding tool 26. A suitable motor 27 is employed for rotating the spindle

and may be directly connected thereto or connected by means of a belt 28, as illustrated.

This grinder unit 5 is mounted on a cross sliding table 29 adapted to reciprocate transversely of the table 3. A suitable manually operated wheel 30 provided with a section 31 having graduations thereon is fixed to a shaft 32 which is in turn connected by means of gearing 33 to a lead screw 34 connected to the table 29 for adjusting the table to cutting position and this lead screw connection permits very fine adjustment of the table.

This table 29 and grinder unit, as before explained, are adapted to reciprocate transversely of the work carrying table and this reciprocating movement is derived from a cam shaft 35 gear connected with the gearing 18 driving the work spindle 15. Thus, it will be seen that the motor F drives both the work spindle and the cam shaft 35 and a definite speed ratio of rotation of each may be obtained by the proper selection of gearing.

Mounted on the opposite end of this cam shaft is the master cam 36 and this cam engages a roller 37 of a roller holding latch or lever 38 pivotally connected or fastened by means of a stud 39 to the frame of the machine in such manner that the pivot point will always bear the same fixed relation to the cam shaft 35.

The transverse slide or table 29 is provided with a vertically positioned T-slot 40 for the reception of a block 41 contacting the lever 38 and this block may be moved up or down in such manner that its position, together with the movement of the pivoted lever 38 by the cam 36, will limit or control the reciprocating stroke of the table 29.

The complete operation of the machine and the relationship of the various parts will now be described.

A work piece, as 17, to be ground with four cam surfaces is inserted in the chuck or holding means 16 and the tool carrier 5 is provided with the necessary grinding tool and properly positioned by the manually operative wheel 30. Thereupon the motor 27 is started to start the grinding tool rotating at a very high speed. The hydraulic mechanism is then started to cause fluid to be supplied to reciprocate the work table 3 and the lever 12 is pressed into engagement to control operation of the pilot valve E to control the direction of flow of the fluid so that the table will be shifted back and forth.

During these operations, the motor F is started by means of the hand controlled valve D to effect rotation of the gear trains 18 et seq. and thereby the work spindle 15 and also the cam shaft 35 and cam 36. The gearing illustrated is such that the cam 36 will be rotated at four times the speed of the work spindle 15 so that the tool may grind the four desired cam surfaces by reciprocating the transverse tool table or slide 29 four times to each rotation of the work and during the entire operation of the machine, the work table 3 is reciprocated back and forth at a very high rate of speed to insure an even grinding of the cam surfaces.

From the foregoing it will be understood that while I have described the reciprocation of the work table in one direction with the tool slide reciprocating transversely thereto, these movements may be reversed if desired or one table may have a dual reciprocation while the other remained in a fixed position.

It is to be understood that by describing in de-

tail herein any particular form, structure or arrangement, it is not intended to limit the invention beyond the terms of the several claims or the requirements of the prior art.

Having thus explained the nature of my said invention and described a way of constructing and using the same, although without attempting to set forth all of the forms in which it may be made, or all of the modes of its use, I claim:

1. A cam grinding machine having a reciprocating work carrier rotatable about its longitudinal axis for varying the angle of the work, means for rapidly reciprocating said carrier, a rotatable work spindle carried by said carrier, means for rotating said spindle, a reciprocating tool carrier reciprocal transversely of said work carrier, means for reciprocating it, a rotatable spindle carried by said tool carrier, means for rotating it, and means for adjusting the position of said tool carrier transversely of said work carrier.

2. A cam grinding machine having a reciprocating work carrier rotatable about its longitudinal axis for varying the angle of the work, means for rapidly reciprocating said carrier, a rotatable work spindle carried by said carrier, means for rotating said spindle, a reciprocating tool carrier reciprocal transversely of said work carrier, means for reciprocating it, said last means including a cam rotated by the work spindle rotating means, a rotatable spindle carried by said tool carrier, and means for rotating it.

3. A cam grinding machine having a reciprocating work carrier rotatable about its longitudinal axis for varying the angle of the work, means for rapidly reciprocating said carrier, a rotatable work spindle carried by said carrier, means for rotating said spindle, a reciprocating tool carrier reciprocal transversely of said work carrier, means for reciprocating it, said last means including a cam rotated by the work spindle rotating means, means for rotating said cam at a speed ratio relative to the speed of rotation of said spindle, a rotatable spindle carried by said tool carrier, and means for rotating it.

4. A cam grinding machine having a reciprocating work carrier rotatable about its longitudinal axis for varying the angle of the work, means for rapidly reciprocating said carrier, a rotatable work spindle carried by said carrier, means for rotating said spindle, a reciprocating tool carrier reciprocal transversely of said work carrier, means for reciprocating it, said last means including a cam rotated by the work spindle rotating means, means for rotating said cam at a speed ratio relative to the speed of rotation of said spindle, means for varying said speed ratio, a rotatable spindle carried by said tool carrier, and means for rotating it.

5. A cam grinding machine having a pair of carriers each provided with a rotatable spindle, one carrying a work piece having a cam to be ground and the other a cam grinding tool, and reciprocal transversely of each other, means for reciprocating one carrier at high speed, said reciprocating means including fluid valve operating means for controlling the stroke of the high speed carrier, and means for preventing shock to said fluid valve operating means.

6. A cam grinding machine having a pair of carriers each provided with a rotatable spindle, one carrying a work piece having a cam to be ground and the other a cam grinding tool, and reciprocal transversely of each other, means for reciprocating one carrier at high speed, one of

said carriers reciprocating at a speed ratio relative to the speed of rotation of the spindle of the other, said reciprocating means including fluid valve operating means for controlling the stroke of the high speed carrier, and means for preventing shock to said fluid valve operating means.

7. A cam grinding machine having a pair of carriers each provided with a rotatable spindle, one carrying a work piece having a cam to be ground and the other a cam grinding tool, and reciprocal transversely of each other, means for reciprocating one carrier at high speed, one of said carriers reciprocating at a speed ratio relative to the speed of rotation of the spindle of the other, said reciprocating means including fluid valve operating means for controlling the stroke of the high speed carrier, means for preventing shock to said fluid valve operating means, and means for changing the relation of said speed ratio.

8. A cam grinding machine having a reciprocating work carrier rotatable about its longitudinal axis for varying the angle of the work, fluid means for rapidly reciprocating said carrier, means for controlling the stroke of said reciprocating carrier, means for preventing shock to said fluid means, a rotatable spindle carried by said carrier, fluid means for rotating said spindle, means for changing the speed of rotation of said spindle, a reciprocating tool carrier reciprocal transversely of said work carrier, fluid means for reciprocating it, means for controlling the stroke of said last reciprocating carrier, means for controlling the speed of reciprocation thereof, means for adjusting the position of said last carrier, a rotatable spindle carried by said last carrier, and means for rotating it.

9. The machine of claim 8 in which the means for reciprocating the tool unit includes a rotating cam.

10. The machine of claim 8 in which the means for reciprocating the tool unit includes a rotating cam so connected with the rotatable work spindle operating means that the work spindle and cam will rotate at different relative speeds.

11. A cam grinding machine comprising a reciprocating table, fluid controlled means for reciprocating said table, fluid valve operated means for controlling the stroke of the table, a work holder carried by the table, a rotary spindle carried by said work holder, means for rotating said spindle, a reciprocating tool unit, means for adjusting it, cam means for reciprocating it and having connection with the means for rotating the work spindle and at predetermined speed ratio relative thereto, and means cooperating with said cam means for controlling the stroke of the reciprocating tool unit.

12. A cam grinding machine having a reciprocating work carrier, fluid means for rapidly reciprocating said carrier, a rotatable work spindle carried by said carrier, fluid means for rotating said spindle, a reciprocating tool carrier reciprocal transversely of said work carrier, fluid means for reciprocating it and including cam operated means connected with the rotary work spindle operating means, a rotatable spindle carried by said tool carrier, means for operating it, and means cooperating with said cam operated means for controlling the stroke of the tool unit.

13. A cam grinding machine comprising a reciprocating table, fluid controlled means for reciprocating said table, fluid valve operated means

for controlling the stroke of the table, means for preventing shock to the said fluid valve operated means, a work holder carried by the table, a rotary spindle carried by said work holder, means carried by said spindle for supporting a cam to be ground, means for rotating said spindle, a reciprocating tool unit, means for adjusting it, and cam means for reciprocating it and having connection with the means for rotating the work spindle and at a predetermined speed ratio relative thereto.
